MACHINE FOR REINFORCING INSOLES

Norman E. Mariner, Beverly, Mass., assignor to
United Shoe Machinery Corporation, Flemington, N. J., a corporation of New Jersey

Application August 6, 1941, Serial No. 405,654

42 Claims.

(Cl. 12—20)

This invention relates to machines for applying reinforcing material to insoles such, for example, as are used in the making of welted shoes, and particularly to machines for applying a strip of fabric such as duck or canvas to the inner face of the rib and to the body of the insole adjacent to the rib. Machines of this type are disclosed in Letters Patent of the United States No. 2,242,248 and No. 2,296,847, granted May 20, 1941, and September 29, 1942, respectively, on applications of Stanley M. Griswold and Russell K. Nash.

Objects of this invention are to provide a machine of this type which will be more efficient, more durable and better adapted for quantity production without, however, sacrificing any of the advantages of said prior machines.

As in said prior machines, the illustrated machine comprises a lower feed roll to engage the unribbed face of an insole, an upper feed roll to engage the feather of the insole, said rolls being separated to receive the work and pressed together to cause the work to be fed, and an applying roll movable into and out of operative position with respect to the ribbed face of the insole and acting to apply a cemented strip to the inner face of the rib and to the adjacent body of the insole. As heretofore, manually operated means, for example a treadle, is utilized to press the feed rolls together and to move the applying roll into operative position.

A feature of the present invention consists in providing separate and adjustable yielding devices through which the feed roll and the applying roll are operated. Thus, the pressure of the feed rolls upon the work may be controlled independently of the pressure of the applying roll upon the strip being applied and greater pressure exerted upon the feed roll than upon the applying roll.

Another feature of the invention consists in so mounting and operating the feed rolls that the space between them is unobstructed and the machine is thereby adapted for operation on insoles having portions projecting abnormally far beyond the rib, as in insoles having a shank-supporting extension commonly known as a "cookie."

A still further feature of the invention relates to the strip-applying device or applying roll and consists in making one part of the applying device yieldable with respect to another part of it so that engagement of one part with a thick portion of the insole will not prevent pressure of another part on a thinner portion of the in-

sole. As illustrated, the part of the applying device which engages the strip over a thinner portion of the insole, for example over the inside channel, is mounted to yield upwardly with respect to the remainder of the device which engages the strip over a portion of the insole of full thickness. Provision is made for setting the yieldable portion of the device at different distances below the remainder of the device. As illustrated, the applying device comprises a plurality of spurred disks to engage the strip over the portion of the insole of full thickness and another spurred disk to engage the strip over the channel of the insole, said last-named disk being mounted upon a slide having a surface formed flush with the disk to rub the strip into the channel and another surface formed to rub a portion of the strip against the inner face of the rib, said slide and the disk mounted thereon being yieldable to operate uniformly in channels of different depth.

These and other features of the invention, including various convenient adjustments and novel combinations and arrangements of parts, will be more fully understood from the following description when read in connection with the accompanying drawings and will be pointed out in the appended claims.

In the drawings,

Fig. 1 is a side elevation of a machine embodying the present invention;

Fig. 2 is a sectional detail of parts shown in Fig. 1;

Fig. 3 is an elevation, partly in section, taken from the right-hand side of the machine;

Fig. 4 is an enlarged sectional view of the applying roll;

Fig. 5 is a sectional detail on the line V—V of Fig. 4;

Fig. 6 is a detail, partly in section on the line VI—VI, of parts shown in Fig. 3;

Fig. 7 is an elevation, partly in section, taken from the left-hand side of the machine;

Fig. 8 is a front elevation of the head of the machine;

Fig. 9 is an exploded view of the strip-cutting mechanism;

Fig. 10 is a view, partly in section, of yielding mechanism through which the upper feed roll is operated;

Fig. 11 is a detail, partly in section, of the applying roll and receiving unit;

Fig. 12 is a perspective view of an insole one side of which has been reinforced by operation of the machine; and

Fig. 13 is a similar view showing both sides so reinforced.

Referring to Fig. 1 of the drawings, the machine comprises a triangular base 20 and a vertical column 22 the upper end of which is bored to receive a hollow neck 24 which is adjustably held in the column 22 by clamping bolts 26. To the neck 24 is secured a box or casing 28 on which a head casting 30 is mounted. The head 30 is provided with bushed bearings 32 for a shaft 34 which carries the lower feed roll 36 at one end and a driving pulley 38 at the other. Power is supplied to the pulley through a belt 40 from a countershaft pulley 42 carrying a disk 44 which may, at will, be pressed toward the rear face of a pulley 46 driven by a belt 48 from a motor 50, there being between the disk 44 and the pulley 46 a loose friction disk 52 of leather and a spring (not shown) to separate the pulley and the disk 44.

A frame or yoke 54 (Fig. 3) is mounted for movement about a horizontal axis directly over the rear bearing 32 by means of pins 56 having conical ends arranged to enter conical recesses on opposite sides of the yoke, the pins being held in place by draw bolts 58 (Fig. 7). Front and rear bearings 60, 62 are provided in the yoke 54 for a shaft 64 which carries an upper feed roll 66. The upper feed roll is driven by a gear 68 pinned to the shaft 64 and meshing with a gear 70 pinned to the shaft 34. The arrangement is such that when the yoke 54 is swung about the center 56 to cause the feed roll 66 to engage the feather of the insole the shaft 64 will be substantially parallel to the shaft 34 and hence the teeth of the gears 68, 70 will be parallel to each other and there will be a free space between the bearings 32 and 60 high enough to permit passage through it of a lateral projection, such as a cookie, on the insole.

Associated with the upper feed roll 66 is an outside guide 72 (Fig. 6) the rear portion of which has parallel sides which engage a corresponding vertical recess 74 formed in a block 76. The block 76 has parallel sides which engage a corresponding horizontal groove in the yoke 54. A screw 78 passing through a horizontal slot in the block 76 and threaded in the yoke 54 serves adjustably to secure the block 76 to the yoke, and a screw 80 passing through an enlarged hole in the guide 72, through a slot in the block and threaded into the yoke 54, serves adjustably to hold the guide 72 in vertically adjusted position relatively to the block 76 and to hold both the guide and the block to the yoke 54. The guide 72 has adjacent to the upper feed roll 66 (Fig. 8) a curved face corresponding to the curvature of the roll and substantially in contact therewith. The above-described heightwise and horizontal adjustments of the guide 72 enable it to be located with respect to the feed roll 66 properly to engage the outer face of the rib and the feather of the insole, thus to assist in guiding the insole past the feed roll.

The mechanism for moving the upper feed roll 66 toward and from the lower feed roll 36 comprises a rockshaft 82 journaled in the frame 30 (Fig. 3) and having fixed thereon a lug 84 through the outer end of which is threaded a screw 86 which is locked in adjusted position by a nut 88. Freely pivoted on the rockshaft 82 is a member 90 (Fig. 10) which is held from rearward movement on the shaft 82 by a collar 92 fixed to the shaft (Fig. 3). A plunger 94 (Fig. 10) extends through the member 90 which is

counterbored to receive a collar 96 fixed to the plunger 94 and is further counterbored and threaded at 98 to receive a threaded sleeve 100 through which the plunger 94 freely passes. Between the collar 96 and the sleeve 100 is a compression spring 102 the initial tension of which may be varied by turning the sleeve which may be locked in adjusted position by tightening a lock nut 104 threaded on the sleeve. The yoke 54 carrying the upper feed roll 66 is held normally in raised position by a spring 106 (Fig. 3) fastened at its lower end to the yoke 54 and at its upper end to a pin 108 on the frame 30. The yoke is connected by a ball-ended link 110 to the member 90 (Fig. 10), the upper ball of the link being held in the member by a slotted plate 112 and the lower end being held in the yoke 54 by a similar plate 114. The ball-ended link 110 permits longitudinal movement of the shaft 82 for a purpose later explained. Turning of the shaft 82 causes the screw 86, after a period of lost motion determined by the setting of the screw, to engage the plunger 94 and move the member 90 with the shaft 82, thus pressing downwardly on the link 110 and causing the yoke 54 and the upper feed roll to swing about the center 56, overcoming the spring 106. When the work is in the machine and hence approaching movement of the rolls is obstructed, the spring 102 will yield and the pressure of the roll 66 upon the work will be determined by the initial tension to which the spring was set by adjustment of the sleeve 100. When no work is in the machine, the rolls are prevented from engaging each other by a stop screw 116 threaded through a portion of the frame 30 and held in adjusted position by a lock nut 118. After a predetermined movement of the shaft 82, a lug 120 on the member 90 engages the screw 116 and prevents further movement of the yoke and feed roll; further rotation of the shaft 82 by compression of the spring 102, however, is permitted.

To the rockshaft 82 is pinned a lever one arm 122 of which extends to the left (Fig. 8) and is pivoted at 124 to a rod 126. The rod 126 (Fig. 2) has a collar 128 at its lower end which can slide freely in a sleeve 130 which is secured to a rod 132. An apertured plug 134 through which the rod 126 passes is threaded into the upper end of the sleeve 130 and has threaded thereon a lock nut 136. Between the plug 134 and the collar 128 is a compression spring 138 the initial tension of which may be adjusted by turning the plug 134. The rod 132 is urged upwardly by a tension spring 140 (Fig. 1) connected between a collar on the rod and a pin on the machine frame. The rod 132 passes through a sleeve 142 which is held against depression by a clamp collar 143. The sleeve 142 is pivoted at 144 to the long arm 146 of a lever journaled at 148 in the column 22. Forwardly of the fulcrum 148 a short arm 150 of the lever is pivoted to a rearwardly inclined link 152 which in turn is pivoted at 154 to an upwardly extending, rearwardly inclined arm 156 of a bell-crank lever, the other arm 158 of which is formed as an operating treadle 160. The bell-crank treadle lever 156, 158 is pivoted to the base at 162 and depression of the treadle will cause straightening of the toggle formed by the arm 156 and the link 152 to cause downward movement of the lever arm 146 and, through the rods 132, 126, to cause counterclockwise movement of the shaft 82. The spring 138 should be so set that it will not be substantially compressed until the spring 102 has yielded.

Depression of the treadle 160 to bring the rolls 36, 66 together causes rotation of the rolls by power. On the rod 132 (Fig. 1) is a collar 164 which, as the rod is depressed, engages a spring 166 encircling the rod and resting on a bifurcated arm 168 of a bell-crank lever pivoted at 170 the other arm 172 of which engages the hub of the pulley 42. The collar 164 is initially considerably above the spring 166 so that only during the later portion of the depression of the treadle will the collar engage the spring and rock the bell-crank lever 168, 172 to press the friction disk 52 against the face of the motor-driven pulley 46, thus causing the feed rolls to be driven. When the treadle is released the disk 44 engages a braking pad 173 adjustably fixed on the machine and is quickly brought to rest.

Counterclockwise movement of the shaft 82 to bring the feed rolls together also moves the tape-applying roll into operative position. As shown in Fig. 11, a casting 174 is fixed to the front end of the rockshaft 82 and is bored to receive an electric heating unit 176. On the left-hand end of the casting 174 (Fig. 11) is mounted a strip-applying device or applying roll indicated generally by the numeral 178 and shown in detail in Figs. 4 and 5. A body member or carrier 180 secured by screws 182 to the casting 174 carries a fixed stud 184 on which is mounted a plurality of spurred disks or rolls 186. In the body member 180 is formed a guideway which is vertical, as shown in Fig. 4, and receives a slide 188. On the slide 188 is formed a face 190 which engages one marginal portion of the strip and rubs it against the inner face of the rib of the insole. Opposite the face 190 the slide 188 has formed thereon a stud 192 upon which is mounted for free rotation another spurred disk or roll 194. The disk 194 therefore is movable with the slide 188 relatively to the disks or rolls 186. The slide 188 is bored at 196 to receive a compression spring 198 the upper end of which abuts an angle plate 200 secured by screws 202 to the body member 180. Downward movement of the slide 188 in response to pressure of the spring 198 is limited (Fig. 5) by a ledge 204 formed on a plate 206 having slots through which cap screws 208 pass and are threaded into the body member 180. By loosening the screws 208 the plate 206 may be adjusted to vary the amount the disk 194 is held by the spring 198 out of axial alignment with the disks 186. The periphery of the disk 194 is substantially flush with the lower end of the slide 188. The end face of the slide 188 and the periphery of the disk 194 engage the portion of the strip which is laid in the channel of the insole while the disks 186 lay the inner marginal portion of the strip against the body of the insole. Since the depth of the channel may vary somewhat, not only in different insoles but even in the same insole, it is desirable to have the disk 194 yield heightwise of the insole rib so that all the disks will constantly engage the work notwithstanding variations in the depth of the channel. This is accomplished by the construction shown.

Also mounted on the casting 174 are a guide 210 for the strip S, a tensioning device 212 for the strip, a finger 214 for pressing the strip against the applying roll 178 as the roll moves into operative position, an inside guide 216 mounted on the finger 214, a strip guide 218 adjacent to the applying roll which bends downwardly one marginal portion S' of the strip, and a member forming part of the guide 218 and having an edge 220 about which the marginal

portion S' of the strip is bent to bring it into a position parallel to the inner face of the rib, all of which parts, except as noted below, are constructed and operated substantially as explained in the above-mentioned patents. In the present construction, the finger 214 (Fig. 11) has projecting from its rear face a stud 222 carrying a roll 224 which engages a fixed cam 226 secured to the machine frame by a screw 228. The roll 224 is held against the cam 226 by a spring 230 connected at one end to a pin 232 carried by the finger 214 above its pivot 233 and at the other end to a pin 234 on the casting 174. When the shaft 82 is rocked to swing the applying roll 178 into operative position, the roll 224 moves down the face of the cam 226 and, when it reaches a sharply inclined portion 236 of the cam face, the spring 230 causes the finger 214 to swing abruptly toward the strip S and press it against the applying roll 178. Thus, early in the movement of the applying roll the strip is pressed against the spurs with which the roll is provided.

During the movement of the applying roll 178 into operative position a compression spring 240 (Fig. 3) on the shaft 82 between the frame 30 and the lug 84 is allowed to expand to move the shaft 82 longitudinally to cause the face 190 of the slide 188 to press the marginal portion S' of the strip against the inner face of the insole rib. The longitudinal movement of the shaft 82 is controlled by a cam piece 242 (Fig. 7) pivoted on the shaft 82 and adjustably held by a screw 244 to the rear face of the lever arm 122. The screw 244 passes through a slot in the cam piece 242 so that when the screw is loosened the cam piece may be adjusted about the shaft 82 to vary the location of a drop 246 on the cam piece with respect to a roll 248 mounted on a rod 250 which is threaded through the frame 30 and carries at its outer end a lock nut 252. The roll 248 initially engages a flat surface 254 on the cam piece 242 and prevents longitudinal rearward movement of the shaft 82 in response to pressure of the spring 240. When the applying roll approaches the operating position, however, movement of the cam piece has brought the drop 246 opposite the roll 248, allowing the shaft 82 to move rearwardly in response to the spring 240. The time of movement of the shaft 82 may be varied by adjusting the cam piece 242, as explained, and the initial position of the surface 190 of the slide 188 relatively to the work may be varied by turning the threaded rod 250 to adjust the roll 248 lengthwise of the shaft 82, this adjustment being desirable to accommodate insole ribs of different thickness.

To prevent the spurs on the applying roll 178 from engaging the lower feed roll 38 when no work is in the machine, rotation of the shaft 82 is limited in a counterclockwise direction by a stop screw 256 (Fig. 7) threaded through the frame 30 in position to be engaged by a projection 258 formed on the lever arm 122.

The reinforcing strip S is led from a suitable reel (not shown) through a guide 260 (Fig. 8) on the upper end of an arm 262 of an angle lever pivoted at 264 to a plate 266 fastened to a bracket 268 secured to the frame 30. The guide 260 comprises two ears separated a distance equal at least to the width of the strip, the strip being held between the ears by a pin 270 passing through the ears of the guide. Opposite the pin 270 is a roll 272 mounted on a screw 274. From the guide 260 the strip passes through the guide

210 and the guide 218 to the applying roll 178. The strip is prepared for application to the insole by coating one side of it first with a thermoplastic stiffening material and then with latex cement. Since the strip is coated with thermoplastic stiffening material, it is desirable to heat it just before its application to the insole to render it limp and hence in condition for convenient application. Accordingly, as herein shown, a relatively stationary heating element 276 is pivoted at 278 to the plate 266. The element 276 is urged against an eccentric screw 280 by a spring 282 connected at one end to the element 276 above its pivot 278 and at the other end to a pin 284 on the plate 266. By turning the screw 280 the position of the element 276 about the pivot 278 may be varied. When the treadle is depressed to bring the applying roll into operative position, the strip guides 210, 260 are moved toward the heating element 276 to present a 20 length of tape between them in a position parallel to the heating element and slightly spaced therefrom, the distance the strip is spaced from the heating element being determined by contact with the end of the guide 210 with the element at one end and by engagement of the pin 270 with the element at the other. The guide 210 is, of course, moved toward the heating element by the counterclockwise rotation of the shaft 82 and movement is imparted to the guide 260 from the shaft 82 by an arm 286 secured to the shaft and connected by a compressible link to an arm 288 of the angle lever pivoted at 264. The link comprises a rod 290 which passes through a hole in the arm 288 and has fixed thereto above the arm a collar 292 having knife-edge contact with the arm 288 and below the arm is a similar loose collar 294, between which and a fixed collar 296 on the rod is a compression spring 298. It will be seen that as the shaft 82 is rocked counterclockwise the arm 286 will push upwardly through the spring 298 against the arm 288 and move the arm 262 about the pivot 264 to move the guide 260 toward the heating element 276 and at the same time movement of the shaft will cause the guide 210 to move toward the heating element. After contact of the pin 270 of the guide 260 with the heating element, further movement of the rockshaft is permitted by compression of the spring 298. The position of the heating element may be adjusted by turning the screw 280 so that the guide 210 will not engage the element until the applying roll 178 has reached its operative position substantially in axial alignment with the feed roll 68.

In Fig. 8 the applying roll 178 is shown in its highest position as determined by a link 300 pivoted to an arm 301 on the rockshaft 82 and carrying a pin or roll 302 which, as shown, is in engagement with the deeper notch of a rocking cam 304. Upon the next operation of the machine the roll 302 will engage the shallower notch of the cam 304 and arrest the applying roll 178 before it reaches the position shown, this action and its purpose being more fully disclosed in the patents above mentioned.

After the application of the strip to one side of an insole, for example from its toe end to the breast line, the upper face of the insole is brought into contact with a stop 306 and the mechanism for severing the strip, now to be described, will be operated.

The severing mechanism, which is best shown in Figs. 7 and 9, comprises a base plate 308 which is secured by screws 310 to a horizontal shelf 312

formed on the frame 30. The base plate 308 is formed on its upper side (Fig. 9) with a T-guide in which a T-slide 314 is fitted. The front end 316 of the slide is inclined upwardly at an angle of about 30 degrees to the horizontal and has secured thereto a shear blade 318. A cooperating shear blade 320 is pivoted at 322 to the portion 318 of the slide and is provided rearwardly of its pivot with a roll 324 held thereon by a screw 326. On the slide 314 is an operating slide 328 having an inclined slot 330 to engage the roll 324 and being held to the slide 314 for limited sliding movement with respect thereto by screws 332 passing through slots 334 in the slide 328 and threaded into holes 336 in the slide 314. Movement of the slide 314 with respect to the plate 308 is limited by a screw stud 338 which passes through a slot 340 in the plate 308 and is threaded into the slide 314.

The stop 306 (Fig. 9) is formed on the front end of a forwardly and upwardly inclined arm 342 which is secured by screws 344 to the plate 308, the screws entering threaded holes 346 in the plate. A latch plate 348 is pivoted to ears 350 upstanding from the arm 342 and the pivot pin is held in place by lugs 352 formed on a flat spring 354 secured to the arm 342 at 356 and bearing against a square edge on the latch plate 348 to hold the plate yielding in horizontal position. When the parts are assembled, the head of the screw 326 which holds the roll 324 on the blade 320 projects upwardly beyond the slot 330 and the latch plate 348 lies over the screw head so that initially the head engages a ledge 358 on the under side of the latch plate, the ledge preventing closing of the shears until they have reached operating position.

The shears are operated by an arm 360 (Fig. 7) on a rockshaft 362 the upper end of the arm 360 being connected to the operating slide 328 by a screw passing through the arm and threaded into a hole 364 in the operating slide. Rearward and forward movements of the arm 360 are limited respectively by stop screws 366, 368 (Fig. 7) which are threaded into the frame 30 and provided with set nuts, suitable surfaces 370 being formed on the arm to engage the screws. The stop screws prevent the shock of the operation of the arm 360 by the solenoid from being transmitted to the shear-closing mechanism. The rockshaft 362 (Fig. 1) extends into the casing 28 where it is provided with an arm 372 connected by a link 374 to an armature 376 of a solenoid 378 supplied with current by leads 380. A grasshopper spring 382 is arranged to raise the arm 372 and the armature of the solenoid. Supply of current to the solenoid is controlled by a push button switch 384 located in a switch box 386 secured to the front of the column 22. A knee lever 388 is pivoted at its rear end to the column 22 and at its front end is provided with a knee pad 390. Between its ends the lever 388, when swung to the operator's left, will close the push button switch 384 to supply current to the solenoid, causing the link 374 to be drawn down and the arm 360 to be swung forwardly, thus moving the operating slide 328 which, since the shears 316, 318 are held from movement by the ledge 358 on the latch 348, causes the slide 314 to move forwardly to carry the shears into operative position where the blades embrace the strip. When the blades have reached this position, the head of the screw 326 is forwardly beyond the ledge 358 on the latch plate 348 and the shears are then closed to sever the strip by

further movement of the slide 328 relatively to the slide 314, the inclined slot 330 then acting on the roll 324 to close the shear blades.

To prevent operation of the shear blades accidentally or otherwise when the applying roll is in operative position, means is provided to prevent operation of the lever 388 to close the switch when the treadle is depressed. The shaft 148 (Fig. 1) extends to the outside of the column 22 where it is provided with a short, forwardly extending arm 392. Above the front end of the arm is a rod 394 guided for vertical movement in lugs 396 formed on the column 22. The rod is held normally depressed by a spring 398 located on the rod between the upper lug 396 and a collar 400 fixed to the rod. When the treadle is depressed, the arm 392 moves the rod upwardly, causing its upper end to enter a hole in the lever 388, thus preventing movement of the lever to close the switch while the tape-applying mechanism is in operation.

The plate 266 to which the heating element 276 is pivoted forms the bottom of a casing to which is hinged at 402 a side wall 404 which carries a front wall 406 having a side wall 408. The side wall 406 has a notch 410 to accommodate the lever 288 and a notch 412 to receive a projecting portion of the casting 174 and leads 414 for the heating element 176 when the cover plate 406 is swung about the hinges 402 to enclose the parts mounted on the plate 266. The top and bottom of the casing thus formed are left open.

In the solenoid casing 28 is a distributing block 416 from which the leads 414 for the heating element 176 are carried through a tube 418 and from which leads 420 are carried through a tube 422 to the heating element 276. The distributing block 416 is supplied with current by leads 424 from the same source of current as the leads 389 for the solenoid 378. When the head of the machine is lowered by telescoping the neck 24 in the column 22, the leads, which pass through the casing 28 to a junction box (not shown) at the base of the machine, will be festooned in the box without breaking any connections.

Assuming the parts of the machine to be in the positions shown in Fig. 8, the toe end of an insole I having a rib R (Fig. 12) is placed between the rolls 36, 66 and the treadle 190 depressed. The downward pull on the rod 132 caused by straightening the toggle 152, 156 turns the shaft 82 counterclockwise and swings the applying roll 178 into position in front of the feed roll 66, the reinforcing strip S being pressed against the feed roll by the finger 214. Just as the applying roll 178 reaches operative position, the drop 246 of the cam 242 reaches the roll 248, permitting the spring 240 to move the shaft 82 rearwardly and cause the face 190 on the slide 188 to force the upturned edge of the strip S against the inner face of the rib. At this point the screw 86 carried by the arm 84 on the shaft 82 reaches the plunger 94 and acts through the spring 132 to press the upper feed roll against the feather of the insole. The yielding connection 132 between the rods 126, 132 then permits further depression of the treadle to cause the collar 164 (Fig. 1) to engage the spring 166 and operate the angle lever 168, 172 to press the friction disk 54 against the pulley 45 which is being driven by the motor 50. The feed rolls 36, 66 then begin to rotate and the reinforcing strip S is applied to the insole from the toe to the breast line, as shown in Fig. 12. When this point is reached the operator releases the treadle, holds the insole against the stop 396 and

operates the knee pad 390 to close the push button switch 384, causing the solenoid 378 to pull down on the link 374 and operate the shears 318, 320 to sever the strip.

When the treadle was released, the link 300 (Fig. 8) engaged the shallower notch in the cam 304 so that the applying roll could not swing to its highest position as shown in Fig. 8. Consequently, the portion of the strip S projecting beyond the guide 218 will be shorter than shown in Fig. 8, as is desirable in starting application of the strip at the breast line as is now done. By repetition of the operation, the reinforcing strip is applied to the second side of the insole from the breast line to the toe, whereupon the insole is again brought against the stop 396, the strip severed and pressed against the end of the first strip applied by means of an inclined end face on the stop 396, the insole now being in the condition shown in Fig. 13.

The machine is arranged to be operated from either a standing or a sitting position. When standing, the operator will use the treadle 168 and may keep his heel on the treadle and rest his toe on a projection 430 on the base 20. When it is desired to operate the machine in a sitting position, the head with all the operating instrumentalities is lowered by loosening the clamp screws 26, the collars 143, 164 readjusted and a belt 40 of proper length provided. The operator may then sit on a stool or chair and utilize a treadle 432 which is pivoted at 434 rearwardly of the treadle 168 and has an upwardly extending arm 436 connected by a link 438 to the arm 156 at a point which is as far from the pivot 162 of the forward treadle as its rearward end is from the pivot 434. A toe rest 440 is provided for use with the treadle 432.

To register the number of pairs of insoles produced, a counter 442 (Fig. 3) is provided which is operated by a plunger 444, the arrangement being such that four oscillations of the plunger are required to produce a change in the number indicated on the counter. The plunger 444 is connected by a link 446 to an ear 448 on the lever arm 391 (Fig. 8). Since this lever arm is operated four times in reinforcing each pair of insoles, the counter records the number of pairs of insoles treated.

Having thus described my invention, what I claim as new and desire to secure by Letters Patent of the United States is:

1. In a machine for applying strips of material to insoles, the combination of a pair of feed rolls for gripping and feeding the marginal portion of an insole, means for driving the rolls, strip-guiding means, an applying roll movable toward and from applying position, yielding means through which the applying roll is moved into applying position, and separate yielding means through which the feed rolls are pressed together by movement of the applying roll into applying position.

2. In a machine for applying strips of material to insoles, the combination of a pair of feed rolls for gripping and feeding the marginal portion of an insole, means for driving the rolls, strip-guiding means, a freely rotatable applying roll movable toward and from applying position, yielding means through which the applying roll is moved into applying position, and separate yielding means becoming operative when the applying roll reaches applying position to press the feed rolls together.

3. In a machine for applying strips of material

to insoles, the combination of a pair of feed rolls for gripping and feeding the marginal portion of an insole, means for driving the rolls, strip-guiding means, a freely rotatable applying roll movable toward and from applying position, and means for applying greater pressure to the feed rolls than to the applying roll.

4. In a machine for applying strips of material to insoles, a pair of feed rolls arranged for relative separation and approach, an applying roll arranged for movement of separation and approach with respect to the feed rolls, manually operated means for effecting relative approach of the feed rolls and approach of the applying roll to the feed rolls, and separate adjustable yielding mechanisms one between the manually operated means and one of the feed rolls and the other between the manually operated means and the applying roll whereby more pressure may be applied to the feed rolls upon the work than is applied to the applying roll.

5. In a machine for applying reinforcing strips to insoles, a lower feed roll to receive the insole, an upper feed roll for engaging the feather of the insole, strip-applying means for laying one marginal portion of the strip against the body of the insole and the other marginal portion against the inner face of the rib, means for pressing the rolls together to feed the work, and means for pressing the strip-applying means against the insole, said pressing means being independently adjustable to vary their respective pressures.

6. In a machine for applying reinforcing strips to insoles, the combination of a pair of driven feed rolls, a rockshaft, an arm on the shaft, an applying roll on the arm, a treadle, a treadle rod having thereon a yielding device for turning the rockshaft, a second yielding device between the shaft and the upper feed roll for pressing it toward the lower feed roll when the shaft is rocked, and a lost-motion connection between the second yielding connection and the shaft whereby the applying roll may be moved into operative position by depression of the treadle before the feed rolls are pressed together.

7. In a machine for applying strips of material to insoles, a pair of feed rolls arranged for relative separation and approach, an applying roll arranged for movement of separation and approach with respect to the feed rolls, manually operated means for effecting relative approach of the feed rolls and approach of the applying roll to the feed rolls, and separate adjustable yielding mechanisms one between the manually operated means and one of the feed rolls and the other between the manually operated means and the applying roll whereby the pressure of the feed rolls upon the work and the pressure of the applying roll upon the work may be separately controlled.

8. In a machine for applying reinforcing strips to insoles, a lower feed roll to receive the insole, an upper feed roll for engaging the feather of the insole, strip-applying means for laying one marginal portion of the strip against the body of the insole and the other marginal portion against the inner face of the rib, means for pressing the rolls together to feed the work, an adjustable stop to prevent contact of the feed rolls when no work is in the machine, and means for pressing the strip-applying means against the insole.

9. In a machine for laying strips upon welt insoles to reinforce the ribs thereof, a lower feed roll having front and rear bearings, a yoke mounted for movement about a horizontal axis

located over the rear bearing, a second feed roll having bearings in said yoke whereby a free space between the rolls is provided to permit the passage of a lateral projection on the insole the rib of which is being reinforced, and means for applying a strip to the inner face of the rib and the adjacent body portion of the insole.

10. In a machine for applying strips of material to insoles, a pair of feed rolls, separate shafts carrying the rolls, a yoke in which the shaft for one feed roll is mounted, said yoke being pivoted at a point remote from the work, means for moving the yoke to separate the feed rolls and press them together, one feed roll being adapted to engage the unribbed face of the insole and the other to engage the feather and outer face of the rib, the space between the feed roll shafts permitting the passage between them of lateral projections on the insole which extend outwardly beyond the feather, and means for applying a strip to the inner face of the rib and the adjacent body portion of the insole.

11. In a machine for applying reinforcing strips to insoles, a fixed shaft having separated bearings, a feed roll on the shaft outside of the front bearing, a driving pulley outside of the rear bearing, a yoke pivoted on a horizontal axis above the rear bearing, a shaft having front and rear bearings in said yoke, a feed roll on the front end of the shaft cooperating with the lower feed roll, gears on the shafts adjacent to the rear bearing of the yoke for driving the upper roll from the lower roll, means for separating the rolls to receive the feather of an insole and for pressing them together to cause the insole to be fed, and means for applying a reinforcing strip to the inner face of an insole rib and to the adjacent body portion of the insole.

12. In a machine for applying strips of material to insoles, means for feeding the insole, means for applying a strip to the rib of the insole, means for severing the strip, manually operated means for controlling the applying means, separate manually operated means for controlling the strip-severing means, a reciprocating pin arranged to be moved by one of said manually operated means into the path of the other manually operated means to prevent its action until said first manually operated means is released, and means for retracting the pin when said first manually operated means is released.

13. In a machine for applying strips of material to insoles, the combination of feed rolls, an applying roll, treadle-operated means for pressing the feed rolls together and moving the applying roll into operative position, means for cutting the strip, a knee lever for causing operation of the cutting means, a reciprocating pin arranged to enter a hole in the lever, connections between the treadle and the pin for pushing it into the lever when the treadle is depressed to operate the applying mechanism, and a spring for retracting the pin from the lever.

14. In a machine for applying strips of material to insoles, means for feeding an insole, means for applying a strip to the rib of the insole, means for severing the strip, manually operated means for controlling the applying means, separate manually operated means for controlling the strip-severing means, a reciprocating pin arranged to be moved by said first-mentioned manually operated means into the path of the manually operated means for controlling the strip-severing means to prevent its action until said first mentioned manually operated means is released, and

a spring acting to retract the pin when said first-mentioned manually operated means is released.

15. In a machine for laying strips upon welt insoles to reinforce the ribs thereof, a lower feed roll on a shaft having front and rear bearings, a yoke mounted for movement about a horizontal axis located over the rear bearing, an upper feed roll on a shaft having bearings in said yoke, a guide mounted on said yoke adjacent to the upper feed roll to engage the outer face of the insole rib, and an applying roll acting to lay a strip against the body of the insole inside the rib.

16. In a machine for reinforcing ribbed insoles, means for applying a strip of material to the body of an insole and to the inner face of the rib, means comprising upper and lower feed rolls for feeding the insole toward the applying means, said upper feed roll being movable toward and from the feather portion of the insole, a guide carried by the bearing of the upper feed roll and arranged for adjustment both in the direction of the axis of the upper feed roll and perpendicularly thereto to support the insole rib against outward displacement, and an applying means acting to force the strip against the inner face of the thus supported rib.

17. In a machine for laying strips upon welt insoles to reinforce the ribs thereof, a lower feed roll on a shaft having front and rear bearings, a yoke mounted for movement about a horizontal axis located over the rear bearing, an upper feed roll on a shaft having bearings in said yoke, a guide mounted on said yoke adjacent to the upper feed roll to engage the outer face of the insole rib, and slides movable at right angles to each other, one slide carrying the guide whereby the guide may be adjusted both vertically and horizontally.

18. In a machine for applying strips of material to ribbed insoles, a pair of feed rolls, separate shafts carrying the rolls, a yoke in which the shaft for one feed roll is mounted, said yoke being pivoted at a point remote from the work, means for moving the yoke to separate the feed rolls and press them together, one feed roll being adapted to engage the unribbed face of the insole and the other to engage the feather and outer face of the rib, a guide carried by the yoke adjacent to the feather-engaging feed roll and provision for adjusting the guide both perpendicularly to the axis and lengthwise of the axis of said feather-engaging roll, and means for applying a strip to the inner face of the rib and the adjacent body portion of the insole.

19. In a machine for applying reinforcing strips to insoles, a lower feed roll to receive the insole, an upper feed roll for engaging the feather of the insole, a spurred strip-applying roll for laying one portion of the strip against the body of the insole, means for pressing the rolls together to feed the work, means for pressing the strip-applying roll against the insole where it is supported by the lower roll, and an adjustable stop to prevent the applying roll from engaging the lower feed roll when no work is in the machine.

20. In a strip-laying machine, means for feeding the work, means for applying a strip to the work, a pair of shears for severing a strip arranged for bodily movement into operative position, a slide carrying said shears, a second slide for closing the shears, an arm connected to said second slide, means for causing the second slide to operate the first slide before closing the shears, means for operating the arm, and stops for limit-

ing movement of the arm in both directions to relieve said second slide from the shock of operation by said arm.

21. In a strip-laying machine, means for feeding the work, means for applying a strip to the work, a pair of shears for severing a strip arranged for bodily movement into operative position, a slide carrying said shears, a second slide for closing the shears, an arm connected to said second slide, means for causing the second slide to operate the first slide before closing the shears, a solenoid for operating the arm, and stops for limiting movement of the arm in both directions to relieve said second slide from the shock of operation by the solenoid.

22. In a machine for applying strips of material to insoles, a strip-applying device comprising a plurality of rolls mounted for rotation on a relatively fixed axis, and a roll mounted for rotation on a separate axis, said last-named axis being separately supported and arranged to yield relatively to the axis of the other rolls in response to strip-applying pressure.

23. In a machine for applying strips of material to ribbed insoles, a strip-applying device comprising a plurality of rolls, one of the rolls being arranged to lay a portion of the strip against the insole at the base of the rib and to yield relatively to the other roll in response to strip-applying pressure, said other roll being arranged to lay portions of the strip against the body of the insole farther inwardly of the rib.

24. In a machine for applying reinforcing strips to insoles, an applying device comprising a plurality of rolls arranged to apply pressure to the same side of the strip, one of said rolls being mounted to yield relatively to the other roll, and means for varying the initial position of the yieldingly mounted roll relatively to the other roll.

25. In a machine for applying strips of material to insoles, a strip-applying device comprising a rubbing element arranged to yield in response to pressure against the insole, a stud on said element, a roll mounted for rotation on said stud, said element and roll being adapted to engage the strip over a thinner portion of the insole, and a roll mounted independently of the first-mentioned roll with its axis nearly in alignment with that of said first-mentioned roll and arranged to engage the strip over a thicker portion of the insole.

26. In a machine for applying strips of material to ribbed insoles, a strip-applying device comprising a rubbing element arranged to lay a portion of the strip against the inner face of the rib and to yield heightwise in response to pressure against the insole, a disk mounted for rotation on said element to lay a portion of the strip in the channel of the insole, and a roll rotatably mounted on a supporting stud arranged nearly in axial alignment with the axis of said disk, said roll being arranged at the same side of the rubbing element as the disk and being arranged to lay the strip against the body of the insole.

27. In a machine for applying strips of material to ribbed insoles, a strip-applying device comprising a rubbing element arranged to lay a portion of the strip against the inner face of the rib and to yield heightwise in response to pressure against the insole, a disk mounted for rotation on said element to lay a portion of the strip in the channel of the insole, and a plurality of rolls mounted on a supporting stud arranged

nearly in axial alinement with the axis of said disk, said plurality of rolls being arranged at the same side of the rubbing element as the disk and being arranged to lay the strip against the body of the insole.

28. In a machine for applying strips of material to ribbed insoles, a carrier, a strip-applying device mounted on the carrier comprising a rubbing element arranged to lay a portion of the strip against the inner face of the rib and to yield heightwise in response to pressure against the insole, a disk mounted for rotation on said element to lay a portion of the strip in the channel of the insole, and a disk rotatably mounted on said carrier with its axis nearly in alinement with the axis of said first-mentioned disk, said last-named disk being arranged to lay the strip against the body of the insole beyond the channel.

29. In a machine for applying reinforcing strips to insoles, a strip-applying device comprising a plurality of parts, one to engage the strip over the channel of the insole and another to engage the strip as applied to the body of the insole beyond the channel, the first-mentioned part being mounted for yielding movement heightwise of the insole relatively to the other part to force the strip to the bottom of the channel while the other part applies the strip to the body portion of the insole.

30. In a machine for applying reinforcing strips to insoles, a strip-applying device comprising a plurality of rotatably disks, one to engage the strip over the channel of the insole and another to engage the strip as applied to the body of the insole beyond the channel, the first-mentioned disk being yieldingly depressed heightwise of the insole relatively to the other disk to force the strip to the bottom of the channel while the other disk applies the strip to the body portion of the insole.

31. In a machine for applying strips of material to ribbed insoles, a strip-applying device comprising a support, a slide mounted in the support, a rubbing member and a rotatable disk carried by said slide, a spring acting to press the slide against the work, a disk rotatably mounted on the support, and means for moving the support to carry the applying means into and out of operative position with respect to the insole to cause the rubbing member to rub the strip against the inner face of the rib of the insole, the disk carried thereby engaging the strip and forcing it into the channel adjacent to the rib and the other disk acting to lay the strip against the body of the insole.

32. In a machine for applying strips of material to ribbed insoles, a strip-applying device comprising a support, a slide mounted in the support, a rubbing member and a rotatable disk carried by said slide, a spring acting to press the slide against the work, an adjustable stop for limiting movement of the slide in response to said spring, a disk rotatably mounted on the support, and means for moving the support to carry the applying means into and out of operative position with respect to the insole to cause the rubbing member to rub the strip against the inner face of the rib of the insole, the disk carried thereby engaging the strip and forcing it into the channel adjacent to the rib and the other disk acting to lay the strip against the body of the insole.

33. In a machine for applying strips of material to insoles, a carrier movable into and out

of operative position, and a strip-applying device mounted on the carrier, said device comprising a rubbing element arranged to yield relatively to the carrier in response to pressure against the insole and a rotatable element on an axis fixed relatively to the carrier and arranged also to press the strip against the insole.

34. In a machine for applying strips of material to insoles, a carrier movable into and out of operative position, and a strip-applying device mounted on the carrier, said device comprising a rubbing element arranged to engage one marginal portion of said strip and a rotatable element arranged to engage the other marginal portion of the strip, said elements being mounted on the carrier for relative yielding movement heightwise of the insole whereby one element is adapted to apply the strip to a thinner portion of the insole than the other.

35. In a machine for applying reinforcing strips to ribbed insoles having an inside channel, a carrier movable into and out of operative position, a strip-applying device mounted on the carrier comprising a slide movable heightwise of the insole when the applying device is in operative position, said slide having surfaces to rub a marginal portion of the strip against the inner face of the rib and an intermediate portion of the strip against the bottom of the channel, a spring for depressing said slide relatively to the carrier, and a freely rotatable element mounted on the carrier adjacent to said slide and arranged to press the other marginal portion of the strip against the insole.

36. In a machine for applying reinforcing strips to ribbed insoles having an inside channel, a carrier movable into and out of operative position, a strip-applying device mounted on the carrier comprising a member having a surface to rub a marginal portion of the strip against the inner face of the rib and a surface to rub an intermediate portion of the strip against the bottom of the channel, a freely rotatable element mounted on the carrier adjacent to said member and arranged to press the other marginal portion of the strip against the insole, and means permitting relative yielding movement heightwise of the insole rib between the member and the rotatable element.

37. In a machine for applying strips of reinforcing material to ribbed insoles having an inside channel, a carrier movable into and out of operative position, and a strip-applying device mounted on the carrier, said device comprising a rubbing element arranged to yield relatively to the carrier in response to pressure against the insole, said element having surfaces to rub a marginal portion of the strip against the inner face of the rib and an intermediate portion of the strip against the bottom of the channel, and a rotatable element on an axis fixed relatively to the carrier and arranged to press the opposite marginal portion of the strip against the insole.

38. In a machine for applying strips of material to insoles, a carrier movable into and out of operative position, and a strip-applying device mounted on the carrier, said device comprising a rubbing element arranged to engage one marginal portion of said strip and a freely rotatable roll having spurs in its periphery arranged to engage the other marginal portion of the strip, said element and roll being mounted on the carrier for relative yielding movement heightwise of the insole whereby one is adapted to apply the

strip to a thinner portion of the insole than the other.

39. In a machine for applying a reinforcing strip to ribbed insoles, means for advancing the insole past an operating point, an applying device movable into and out of operative position with respect to said operating point, a carrier for the applying device, a finger pivoted on said carrier, a spring for urging the finger toward the applying device, a roll carried by the finger, and a fixed cam engaged by the roll to hold the finger separated from the applying device when the device is in inoperative position, said cam having an abrupt angular face which permits the spring to swing the finger to engage the applying device early in its movement toward operative position.

40. In a machine for applying a reinforcing strip to ribbed insoles, means for advancing the insole past an operating point, an applying roll movable into and out of operative position with respect to said operating point, a carrier for the applying roll, a finger pivoted on the carrier, means for urging the finger toward the applying roll, a roll carried by the finger, and a fixed cam engaged by the finger roll to hold the finger separated from the applying roll when the applying

roll is in inoperative position, said cam permitting the finger to engage the applying roll early in its movement toward operative position.

41. In a machine for operating on shoe parts, a column, a head adjustable heightwise of the column, operating instrumentalities on the head, and two treadles one in advance of the other for controlling said operating instrumentalities whereby when the head is raised the operator 10 may control the machine from a standing position by operating the forward treadle and when the head is lowered may operate the machine by the rear treadle.

42. In a machine for operating on shoe parts, a column, a head adjustable heightwise of the column, operating instrumentalities on the head, a treadle rod for controlling said instrumentalities, a toggle for operating said rod, a treadle for operating the toggle, and a second treadle located 20 rearwardly of the first treadle and linked to said toggle whereby when the head is raised the operator may control the machine from a standing position by operating the first treadle and when the head is lowered may operate the machine by the second treadle from a sitting position.

NORMAN E. MARINER.
